UNITED STATES PATENT OFFICE.

CHARLES K. DAVIS, OF DETROIT, MICHIGAN.

SMEILING-FURNACE.

1,165,393.

Specification of Letters Patent. Patented Dec. 28, 1915.

Application filed August 14, 1915. Serial No. 45,481.

To all whom it may concern:

Be it known that E. CHARLES K. DAVIS, a citizen of the United States, and a resident of Detroit, in the county of Wayne and State of Michigan, have invented a new and Improved Smelting-Furnace, of which the following is a specification.

This invention relates to the reduction of iron ore, and its object is to provide simple and efficient mechanism for producing metallic iron at minimum cost.

This invention consists in combination with a rotary kiln and means for supplying fuel thereto to pre-heat the ore and fluxing material, of a smelting furnace or stack wherein the highly heated ore and fluxing material may be mixed with carbon to reduce the ore.

This invention further consists in pre-heating the air necessary to support combustion in the rotary kiln.

In the accompanying drawings, Figure 1 is a plan and Fig. 2 an elevation of this improved device. Fig. 3 is a plan of the charging end of the rotary kiln. Fig. 4 is a vertical longitudinal section of said end, a portion of the stack being broken away to show the valve therein. Fig. 5 is a vertical section of the smelting furnace on a plane 30 passing through the heater for the air blast.

Similar reference characters refer to like parts throughout the several views.

The various parts of the plant designed to embody the present invention are shown conventionally, the invention residing in combining these parts in a new way and not in the details of construction. The rotary kiln and the fuel feeding device therefore may be the same as those now being employed in burning cement clinker; the smelting furnace may be similar in construction to those now in use although on a much smaller scale, while any well known means may be employed to utilize the heat of the waste gases to pre-heat the air blasts.

The rotary kiln 1 is provided with any desired number of supporting rings 2, which rest on rollers 3 carried by the supports 4. The usual toothed driving ring 5 may be engaged by the driving pinion 6. The lining 7 of the kiln will depend upon the character of the ore to be treated. As shown in Figs. 3 and 4, the upper or charging end of the kiln extends into a pocket in the wall 8 of a flue 9 that connects with a chimney 10 pro-

vided with a damper or butterfly valve 11. In the top 12 of this flue is a charging chute 13 by means of which ore and limestone may be fed to the kiln.

A blower 14 drives a blast of air through the coil 15 located in the flue in the path of the hot gases that are passing from the rotary kiln to the chimney 10, and through the pipe 16 that extends from the coil to the discharge end of the kiln. This discharge end is surrounded by a cowl 17 from which the heated ore and fluxing material passes to the smelting furnace through a passage or chute 18.

Mounted adjacent the cowl is a mixing chamber 19 of any desired construction to which the blast pipe 16 and the fuel conduit 20 connect. The fuel may be powdered coal or gas, preferably producer gas, and the mixed fuel and air enter the kiln through the pipe 22. The smelting furnace 23 is of any desired construction, and at its upper end is provided with an escape pipe 24 for the burned gases, which pipe connects to an oven or heating chamber 25 through which is looped the blast pipe 26, which extends from the blower 27 to the usual tuyers. A hopper 28 for coke, coal or charcoal is mounted above the furnace and a valve 29 controls the discharge of the contents thereof down through the conduit 30, the valve being preferably water-jacketed. From the chamber 25, the gases may pass to the chimney 32. The pressure of the blast in the pipe 26 may be controlled by the valve 25. If desired, a valve 34 may be employed to cut off communication between the furnace and the pipe 26. So also a valve 33 may be mounted between the blower 14 and the coil 15.

The ore and limestone are fed into the kiln through the chute 13, and because of the inclination of the kiln, this material moves toward the smelting furnace as the kiln revolves, being exposed to the intense heat generated by the combustion of the fuel that is forced in through the pipe 22. The pressure within the kiln near the discharge chute 18 is slightly greater than at the lower end of this passage 13, so that the gases in the furnace will not pass into the kiln. This pressure in the kiln may be regulated by means of the butterfly valve 11, and by the valve 35, while the pressure in the furnace may be regulated by the valves 34 and 33. The molten iron may be tapped 110

off at the spout 37 and the slag at the spout 38.

By supplying fresh air and fuel to the rotary kiln the ore and limestone are brought to a very high temperature at a very low fuel cost in comparison to the cost of the fuel burned in the usual smelting furnace. When the ore and limestone finally arrive at the lower end of the rotary kiln, they are met by what is substantially a reducing flame, and the conversion of the ore to metallic iron is imminent. Instead of being exposed when at this very high temperature to the gases from the smelting furnace, which gases are often loaded with sulfur and phosphorus, the ore in the present rotary kiln is roasted in such a manner that if it contains a high percentage of sulfur, this is driven off to a large extent.

10 The ore and limestone pass from the kiln to the furnace at a very high temperature, one at which the silica in the ore and the limestone are about to combine. When this ore falls into the furnace, it is about ready 15 to combine with the carbon of the fuel so that this reduction is substantially immediate. The furnace, therefore, for a fixed production, is much smaller than one of the same capacity where the ore is heated in the 20 furnace. The actual loss in heat units from the furnace will therefore be much less than with the present types of furnaces, and the total amount of carbon required to reduce the ore is less than that required in the present 25 systems where the coke, ore and limestone are fed into the top of the smelting furnace.

The large percentage of ash in the coke required to heat the ore and limestone in the 30 ordinary furnace remains in the furnace and must be carried out by the slag, thus increasing the amount of limestone required. In the present construction, none of this ash is mixed with the ore, for even when powdered coal is used in the rotary kiln, the ash 35 will be carried along by the blast and be deposited in the flue 8 or be carried up the chimney 10.

I claim:—

1. The combination with a rotary kiln, 50 means to charge the kiln at its upper end, means to introduce fuel at the opposite end, a smelting furnace, a conduit to convey the heated contents of the kiln to the furnace and a passage independent of the kiln to 55 convey away the burnt gases from the smelting furnace.

2. The combination of a rotary kiln, means to charge the kiln at its upper end, means to introduce fuel and air under pressure 60 at the opposite discharge end, means to control the pressure of air within the kiln, a smelting furnace, means to convey the heated contents of the kiln to the furnace and a passage independent of the kiln 65 to convey away the burnt gases from the smelting furnace.

3. The combination of an inclined rotary kiln, means to convey away the burnt gases from the upper end of said kiln, an air pipe 70 so mounted that the air passing through it will be heated by such gases, means to charge the kiln at its upper end, means to introduce fuel and heated air under pressure into the lower end of the kiln, a smelting furnace, and means to convey the heated contents of the kiln to the furnace, the pressure within the kiln being sufficient to prevent the passage of gases from the furnace to the kiln.

4. The combination of an inclined rotary kiln, means to convey away the burnt gases from the upper end of said kiln, an air pipe 75 so mounted that the air passing through it will be heated by such gases, means to charge the kiln at its upper end, means to introduce fuel and heated air under pressure into the lower end of the kiln, a smelting furnace, means to convey the heated contents of the kiln to the furnace, and means to prevent the passage of gases from the furnace to the kiln.

In testimony whereof I have signed this specification.

CHARLES K. DAVIS.
